(57) **CLAIM**

The ornamental design for a recording assist device for camera, as shown and described.

DESCRIPTION

FIG. 1 is a front perspective view of a recording assist device for camera;

FIG. 2 is a front view of the recording assist device for camera of FIG. 1;

FIG. 3 is a rear view of the recording assist device for camera of FIG. 1;

FIG. 4 is a left-side view of the recording assist device for camera of FIG. 1;

FIG. 5 is a right-side view of the recording assist device for camera of FIG. 1;

FIG. 6 is a top plan view of the recording assist device for camera of FIG. 1;

FIG. 7 is a bottom plan view of the recording assist device for camera of FIG. 1;

FIG. 8 is a top perspective view of the recording assist device for camera of FIG. 1;

FIG. 9 is a bottom perspective view of the recording assist device for camera of FIG. 1; and,

FIG. 10 is a rear perspective view of the recording assist device for camera of FIG. 1 in which a camera in broken lines is provided to illustrate an example environment.

Features shown in broken lines in FIGS. 1, 2, 3, 4, 5, 7, 8, 9, and 10, form no part of the claimed design.
